N. W. WILLIAMS

CARPET

Filed Sept. 10, 1927

UNITED STATES PATENT OFFICE.

NOBLE W. WILLIAMS, OF PHILADELPHIA, PENNSYLVANIA, ASSIGNOR TO HARDWICK & MAGEE COMPANY, OF PHILADELPHIA, PENNSYLVANIA, A CORPORATION OF PENNSYLVANIA.

DESIGN FOR A CARPET.

Application filed September 10, 1927. Serial No. 23,358. Term of patent 3½ years.

To all whom it may concern:

Be it known that I, NOBLE W. WILLIAMS, a citizen of the United States, residing in Philadelphia, Pennsylvania, have invented a certain new, original, and ornamental Design for a Carpet, of which the following is a specification, reference being had to the accompanying drawing, the figure of which is a face view of a carpet illustrating my new design.

I claim:

The ornamental design for a carpet, substantially as shown.

NOBLE W. WILLIAMS.
